UNITED STATES PATENT OFFICE

JESSE W. BROOKS, OF CHURCH HILL, TEXAS.

DESIGN FOR A FENCE-POST.

SPECIFICATION forming part of Design No. 30,959, dated June 6, 1899.

Application filed March 1, 1899. Serial No. 707,404. Term of patent 7 years.

To all whom it may concern:

Be it known that I, JESSE W. BROOKS, a citizen of the United States, residing at Church Hill, in the county of Rusk and State of Texas, 5 have invented and produced a new and original Design for a Fence-Post, of which the following is a specification.

The invention relates to a new and original design for a fence-post; and it has for its object to provide a design of this character that shall be both useful and ornamental.

The leading feature of the design resides in a tapering post-body having a step series of adjoining true cylindrical portions of gradually-increasing diameter, forming horizontal shoulders at their adjacent ends.

In the drawings, Figure 1 is an elevation of a fence-post, showing my new and original design. Fig. 2 is a plan view.

20 Referring to the drawings, 1 designates a fence-post body which tapers from the base to the upper end, and the said body is provided at its lower end with a cylindrical base

2. Above the cylindrical base 2 the body of the fence-post is provided with a plurality of 25 true cylindrical portions 3, gradually decreasing in diameter to the top of the post and arranged in a step series. Each succeeding cylindrical portion 3 is smaller than the cylindrical portion 3 immediately below it both in 30 diameter and in length.

At the juncture of the cylindrical portions 3 the fence-post body is provided with horizontal annular shoulders 4, which gradually decrease in diameter from the bottom to the 35 top of the post.

What I claim is—

The design for a fence-post herein shown and described.

In testimony that I claim the foregoing as 40 my own I have hereto affixed my signature in the presence of two witnesses.

JESSE W. BROOKS.

Witnesses:

J. A. HENDRICK,
M. T. LACY.
